UNITED STATES PATENT OFFICE.

WALTER C. TROUT, OF LUFKIN, TEXAS.

CROWN BLOCK.

Application filed April 30, 1923. Serial No. 635,629.

To all whom it may concern:

Be it known that I, WALTER C. TROUT, a citizen of the United States, residing at Lufkin, Angelina County, Texas, have invented a certain new and useful Improvement in Crown Blocks, of which the following is a full, clear, and exact description, such as will enable others skilled in the art to which it appertains to make and use the same.

My invention relates to crown blocks, for particular use on derricks such as are employed in the drilling and pumping of deep wells in the production of oil, gas, sulphur and the like.

In the operation of well drilling, the load to be handled on the derrick is often very great. Lengths of drill-stem and casing aggregating thousands of feet have to be supported upon the cable running over the crown block of the derrick. In the lowering of the pipe into the well, the cable sometimes runs at very high speeds, and it is therefore necessary that the crown block upon which the cable is supported must be constructed to undergo exceptionally severe usage.

It is an object of my invention to provide a crown block whereon the pulleys are mounted with comparatively large bearing surfaces, whereby the wear will be reduced to a minimum.

Another object is to provide a pulley to be used upon bearings of the type described, which may be made of exceptionally hard metal, such as steel, and be strong and durable in operation.

Another object is to provide a crown block and pulleys thereon which will be of few and simple parts, and so formed as to readily support the weight which is suspended thereon.

Further objects and advantages and the means whereby these objects are accomplished will be set forth with greater particularity in the description which follows:

Referring to the drawing herewith, wherein like numerals of reference are applied to like parts in all the views, Fig. 1 is a top plan view of a crown block embodying my invention, wherein two of the pulleys have been shown in central horizontal section; Fig. 2 is an end elevation of the said crown block; and Fig. 3 is a side elevation of one of the pulleys employed on the block.

It is customary in crown blocks employed in well drilling, to provide a plurality of

pulleys supported upon a horizontal framework in such manner that the cable employed in hoisting operations may be run over each of the pulleys in succession, or over any desired number of the said pulleys. In the drawing I have illustrated five of such pulleys, although obviously, the particular arrangement and number of the said pulleys may be varied in any desired manner.

The framework constituting the body of my crown block is made up of a series of longitudinally supporting plates 1, which, as shown in Fig. 2, may be of the ordinary I-beam construction,—these beams being connected at their ends by cross bolts 2 extending from side to side of the said supports. Between the adjacent I-beams and supporting them apart at each end, I provide plates, 3, which are formed to fit the outline of the beam and to support the beams laterally. A central opening is formed in the plate for the purpose of decreasing the weight thereon.

Mounted upon the cross supports 1 are a number of bearing members upon which the pulleys may run. These bearing members are made up of an annular ring or track 4, which has a smooth bearing surface on the periphery thereof, of sufficient width to accommodate the pulley. These bearing rings or tracks are of comparatively large diameter relative to that of the pulley, so that the pulley itself may be in the form of a ring surrounding the bearing. Centrally of the track, and furnishing a support therefor, is a web, 5, which may be cut away on each quadrant as shown at 6, for the purpose of lightness. This web has a vertical rib 7 on each side thereof, which is inclined outwardly from the upper end and forms a bracket connecting with a base plate 8 thereof, which is extended laterally on each side to provide a support adapted to rest upon the supporting I-beams 1. These plates are secured firmly in position upon the I-beams by means of bolts and nuts, 17. Below the supporting bracket thus formed, the web 5 is extended downwardly to connect with the lower portion of the ring.

It will be noted that the support for the bearing thus formed is particularly strong, and also fairly light in construction. The outer edges or sides of the bearing track are extended radially outward to form a channel or track in which the pulley ring 9

may run. The flange 10 thus formed on one side of the bearing is made integral with the track itself. On the other side the flange 11 is made removable so that the pulley 5 may be taken off or replaced, as desired.

The pulley ring 9 has an interior smooth bearing surface to run upon the track 4, and between the said track and bearing surface I prefer to place a series of non-friction bearings 12. These bearings are shown as cylindrical rollers having a small trunnion 13 at each end, which fits within spaced openings in a holding ring 14, to secure the bearings in spaced relation on the track. 10 The outer surface of the pulley is formed with a central groove or channel 15, in which a rope or cable may run. 15

Provision is made for lubricating the bearing rollers by means of small oil ducts 20 16 extending from the inner face of the track, outwardly toward the bearings, as shown particularly in Fig. 1. The opening may be closed under ordinary circumstances by means of a threaded plug, as desired. 25

In the operation of this type of crown block, the block is assembled, as shown in the drawings, each of the supporting brackets and plates being mounted securely upon the frame with the bearings and pulleys 30 placed in proper position thereon and secured in place by means of the plates 11 on the side thereof. The pulley rings are thus adapted to rotate upon a bearing of large diameter. It is possible to make the pulley 35 of larger diameter than is ordinarily the case, for the reason that the bearing is strong and light, and the rings themselves may be of hardened steel. By making the rings larger and the bearings of large diameter, the rotation upon the bearing is not so rapid, and the wear upon the bearing surface is greatly reduced. The use of the 40 roller bearings assist materially in decreasing friction and consequent wear. It will be noted that each of the bearings with the pulley thereon may be removed from the frame by simply removing the securing 45 bolts 17. The parts constituting the block are few and strong, and the liability of breakage and the falling of broken pieces 50 from the crown block upon the operators, will be practically eliminated. 55

The further objects and advantages of my construction will be obvious to one skilled in the art, without further description, it being understood that various

changes in form and arrangement may be made without departing from the spirit of my invention.

What I claim as new and desire to protect by Letters Patent is:

1. A crown block comprising a horizontally disposed frame, a series of pulley bearings on said frame, each bearing comprising an annular vertically arranged track, 60 radially extending marginal flanges on said track forming a channel, a central vertically arranged supporting web for said track, laterally extending plates forming brackets on said web adapted to rest on said frame to support said track, and pulley rings rotatable in said channel on said track.

2. A crown block comprising a horizontally disposed frame, a series of pulley bearings on said frame, each bearing comprising a vertically arranged web, a channel-shaped track thereon, an angular bracket to support said web on said frame and a pulley ring rotatable on each of said bearings. 75

3. A crown block comprising a supporting frame, a series of pulley bearings on said frame, each bearing comprising an annular track, a supporting web centrally of said track, brackets on said web supported by said frame, grooved rings rotatable on said bearings, and non-friction means between said rings and said bearings. 80

4. In a crown block, a pulley ring, a support therefor comprising an annular bearing, a supporting web inside said bearing, brackets formed on said web, a supporting frame for said brackets and means to retain said pulley on said bearings. 90

5. In a crown block, parallel supporting beams, a vertical web having an annular bearing track thereon, laterally extending plates on said web supported on said beams, a grooved pulley ring on said bearing track and means on said track to hold said ring 100 in position thereon.

6. In a crown block a plurality of parallel beams, a vertical web having horizontal plates integral therewith adapted to rest on said beams, a marginal rim on said web constituting a track, a pulley ring rotatable thereon and means on said track to retain said ring thereon. 105

In testimony whereof, I hereunto affix my signature, this the 25 day of April, A. D. 110 1923.

WALTER C. TROUT,
